UNITED STATES PATENT OFFICE.

HOSEA P. ALDRICH, OF SOMERVILLE, MASSACHUSETTS.

SEWING-MACHINE.

SPECIFICATION forming part of Letters Patent No. 393,414, dated November 27, 1888.

Application filed November 10, 1886. Serial No. 218,478. (No model.)

To all whom it may concern:

Be it known that I, HOSEA P. ALDRICH, of Somerville, county of Middlesex, State of Massachusetts, have invented an Improvement 5 in Sewing-Machines, of which the following description, in connection with the accompanying drawings, is a specification, like letters on the drawings representing like parts.

My invention relating to sewing-machines 10 is embodied in a double-thread lock-stitch machine using waxed thread, and especially intended for various kinds of leather work. The main devices for forming the stitch may be and are shown as of usual construction, and comprise an awl operating above the work-support to pierce the material, a hooked needle 15 that enters the hole thus made from below the work-support, a thread guide or looper above the work-support that throws the upper thread into the hook of the needle when projecting 20 above the material, and a shuttle containing the under thread, which is thrown through the loop of upper thread that is drawn down below the under surface of the material being 25 sewed by the hooked needle.

The invention consists, mainly, in details of construction of the devices for presenting the thread to the stitch-forming devices before mentioned; for regulating the tension of the 30 upper and under threads; for taking up the loop in the upper thread after the under thread has been passed through it by the shuttle, and for applying the wax to the thread and retaining the parts properly heated, so 35 that the wax remains soft and pliable, and in various combinations of devices co-operating with the main stitch-forming appliances, as will be hereinafter specified.

Some of the devices forming the subject of 40 this invention are not absolutely essential to the operation of the machine, but are auxiliaries that increase the certainty and positiveness of the operation of the other parts, and thus enable the sewing to be made more rapidly and with greater uniformity than can be effected without such auxiliary devices.

The machine is shown as having an awl-feed; but this is not essential, as any suitable means for feeding the stock may be employed.

50 An important feature of the invention consists in the means employed for controlling the

tension of the upper thread, waxing the thread, supplying it to the stitch-forming devices, and taking up the thread that has been required to form a loop sufficiently large for the shuttle 55 to pass through. The wax for the upper thread is contained in a stationary receptacle or reservoir, (shown as heated by a steam-pipe passing through it,) and from the said reservoir the wax is carried by suitable passages 60 to a take-up device or vibrating arm, upon which is supported the tension-wheel for the upper thread, and also a small waxing-receptacle having perforated nuts at its opposite ends, through which the thread passes from 65 the tension-wheel to the stitch-forming devices. Suitable connections or ports are made by which the moving waxing-receptacle on the vibrating arm or take-up is retained in constant communication with the wax-reservoir, 70 and by which a constant circulation of steam is also maintained on the said arm for the purpose of keeping the small moving wax-receptacle heated, and steam is also kept circulating through pipes along the shuttle-race, so 75 that the shuttle and under thread are kept heated by the conduction of heat through the metallic parts. The tension-wheel is provided with a brake or stop that prevents it from turning while the take-up arm is making its 80 up-and-down movement, and the said brake is released at the end of the upward movement of the arm, by which the last stitch is drawn up, and at this moment enough thread is drawn off over the tension-wheel for the next stitch. 85

The machine is provided with a thread-measuring device which holds the upper thread in such position that the hook of the needle will draw down the loop of thread without causing the thread to run through the hook, thus 90 relieving the thread from the wear which it would otherwise get, and while such a thread-measuring device is not broadly new, it is believed that the arrangement of the said device with relation to the other parts and the means 95 for actuating it are novel. The other novel features will be described in connection with the drawings that illustrate the machine.

Figure 1 is a side elevation of a sewing-machine embodying this invention with parts of 100 the frame-work broken away; Fig. 2, a sectional detail on line X X, Fig. 1, showing in

plan view the thread-guide or looper, the thread-measuring device, presser-foot, work-support, and some of the parts below; Fig. 3, a front end elevation of the machine, showing only the parts at the front end of the machine; Fig. 4, a sectional view through the shuttle-race showing the shuttle and shuttle carrier as seen when looking from the rear toward the front of the machine; Fig. 5, a plan view of the shuttle-carrier, showing the shuttle and a part of the shuttle-race in dotted lines; Fig. 6, a horizontal sectional detail on line $z z$, Fig. 3; Fig. 7, a longitudinal section of the shuttle; Fig. 8, a plan view of the hub or axis of the vibrating take-up arm; Figs. 9 and 10, details illustrating the operation of the looper or thread-guide and thread-measuring device.

The main frame-work of the machine, comprising a base portion, a , that supports the operative devices below the material being sewed, and an arm, a' , that supports the devices above the material, may be of any suitable shape, material, and construction, varying somewhat with the nature of the material to be operated upon. The working parts are all actuated by a main shaft, b , (shown as driven by a pulley, b' , in the usual manner.) There is nothing of novelty in the devices for actuating the awl c , needle d , looper or thread-guide e , and presser-foot f , all of which, except the needle, are shown as actuated by mechanism substantially the same as shown in Patent No. 332,317, granted to me December 15, 1885, to which reference may be had. The actuating mechanism for these parts may be briefly pointed out as follows: The awl-bar c' , which is vertically movable in guides in a carriage, c^2 , is connected by a link, c^3 , with an arm, c^4 , on the shaft c^5 , all best shown in Fig. 3, which shaft is provided at the rear of the machine (see Fig. 1) with an arm, c^6 , connected by a link, c^7 , with a lever, c^8 , provided with a projection that enters a groove in a cam, c^9 , on the main shaft b , and through these connections each rotation of the main shaft causes an up-and-down movement of the awl c at the proper time with relation to the movement of the other parts.

The carriage c^2 , in which the awl-bar moves, is connected by a dovetail guide, as shown in Fig. 1, with the end of the arm a' of the machine, and is horizontally movable on the said guide to produce the feed of the material. This horizontal movement of the carriage is produced at the proper times—namely, in one direction while the awl is in the material, and in the opposite direction when the awl is out of the material—by means of an arm, c^{10} , (see Fig. 3,) on a shaft, c^{12} , extending along the rear of the arm a' , as seen in Fig. 1, the said shaft c^{12} being provided at its other end with another arm, c^{13} , connected by a link, c^{14} , with an arm, c^{15} , actuated by a cam, c^{16} , on the main shaft.

The presser-foot f is supported on a bar, f' , (see Fig. 3,) having a nut or projection, f^2 , at its upper end, and a sleeve, f^3 , free to

move up and down on the said bar, but engaging the projection f^2 in its upward movement, and thus raising the bar and presser-foot from the material being sewed at the time that the lateral or feed movement of the awl takes place. This sleeve f^3 is connected by a link, f^4 , with an arm, f^5 , (see Fig. 1,) on a shaft, f^6 , (shown as a hollow shaft,) having its bearings on the shaft c^5 , although it might have independent bearings, if desired. The said shaft f^6 is provided near the rear of the machine with an arm, f^7 , connected by a link, f^8 , with an arm, f^9 , actuated by a cam, f^{10} , on the main shaft b . These trains of mechanism from the main shaft to the awl, awl-bar carriage, and presser-foot are all substantially alike, except in the shape and positions of the cams, and the arms c^8 , c^{13} , and f^7 , that are actuated directly from the different cams, are all fulcrumed on a rod, c^{20} , supported in brackets a^2 on the base of the machine.

The looper or thread guide e is fastened upon an oscillating shaft, e' , provided with an arm, e^2 , (see Fig. 3,) connected by a link, e^3 , with an arm, e^4 , at the upper end of a vertical rock-shaft, e^5 , having an arm, e^6 , at its lower end engaged and operated by a cam, e^7 , on the main shaft b , as in the patent hereinbefore mentioned.

The thread-measurer g , the function and operation of which will be hereinafter more fully explained, consists of a finger forked or notched at its end, as best shown in Figs. 2 and 10, connected with a sleeve, g' , of the looper-shaft, and is provided with an arm or crank-pin connected by a link, g^2 , with an arm, g^3 , on a vertical rock-shaft, g^4 , provided with an arm, g^5 , actuated by a cam, g^6 , on the main shaft b , and the mode of operation of this connecting mechanism between the main shaft and the thread-measurer is substantially the same as that which actuates the thread-guide, which is the same as shown and described in Patent No. 113,962, granted to me April 25, 1871.

The hooked needle d below the plate or work-support h of the machine is supported on a bar, d' , (see Fig. 4,) connected by a link, d^2 , (see Fig. 1,) with an arm, d^3 , pivoted on a shaft, d^4 , and actuated by a cam, d^5 , on the main shaft b . The said needle-bar d' works in a guide-passage formed in an upright, a^3 , projecting from the base of the machine, the upper portion of which upright forms a shuttle-race, a^4 , which is entirely open at one side, as clearly shown in Figs. 1 and 3.

The shuttle i is shown as made mainly of a single piece of metal of somewhat irregular shape externally, as shown in the various figures, having a longitudinal cylindrical bore, as shown in Fig. 7, and a cap, i' , that screws into the end of the bore and holds the bobbin i^2 in place, said bobbin bearing at one end on a yielding pivot or step, i^3 , and resting at its other end against a friction-plate, i^4 , which may be pressed against the end of the bobbin with greater or less force by a follower, i^5 , having a split threaded stem working in a threaded

opening in the cap i^s , and fastened when properly adjusted by a tapering screw, i^s . By turning the follower i^s inward toward the body of the shuttle the spring at the other end will be compressed, and thus cause greater pressure on the friction disk i^s and increased resistance to rotation of the bobbin i^s until the thread is caused to draw off properly from the said bobbin, the thread passing out through an opening, i^s , in the upper part of the shuttle. It is preferable to wax the thread before winding it on the bobbin i^s , and when the machine is in operation the entire shuttle and inclosed thread are kept heated, by means hereinafter described, sufficiently to keep the thread soft and pliable. The upper thread, k , Fig. 1, is taken dry or unwaxed from a ball or spool and passed through a suitable guide, k' , on an arm, k^s , pivoted at the side of the arm a' of the machine, and from the said guide k' the thread passes around a tension-wheel, k^s , pivoted on the end of the arm k^s and having the resistance to its rotary movement adjusted by a friction device, as is usual on the tension-wheels of sewing-machines, which wheels are not, however, usually placed on the vibrating take-up arm, as in this invention. From the wheel k^s the thread passes through the waxing-receptacle k^t , which is a short cylinder fastened on the end of the take-up arm k^s , and having its ends partially closed by plugs or nuts k^s , having openings through which the thread passes, the thread filling the said openings, so that the wax will not run out, but the thread will be thoroughly saturated with wax in passing through the said waxing-chamber, from which it is carried through the eye of the thread-guide or looper e , which operates to place the thread in the hook of the needle d in the usual manner.

The hot melted wax is supplied from a reservoir, m , having an outlet-pipe, m' , that passes to a ring or collar, m^s , that is stationary on the pin m^s , on which the take-up arm k^s turns, and bears laterally against a ring or collar, m^t , that turns with the arm k^s about the pin m^s as an axis, and is provided with a pipe, m^s , that leads to the waxing-receptacle k^t . This construction maintains a constant communication between the waxing-receptacle k^t and the wax-reservoir m , while permitting the wax-receptacle k^t to move with the arm k^s ; but it is obvious that a flexible duct may be employed to convey the wax from the reservoir to the receptacle, instead of the jointed connection $m^s m^t$. The wax is retained properly melted in the receptacle m by a steam-pipe, n , that passes through the same and out from the receptacle, as indicated at n' , and the said pipe forms a continuous circuit for the flow of steam around all the parts of the machine that have to be heated. It is necessary to keep the arm k^s and wax-receptacle k^t heated, and this is effected as follows: The steam-pipe n' , issuing from the wax-reservoir m , passes to a collar, n^s , (see Fig. 8,) on the pin m^s of the take-up arm k^s , and the said pipe n' connects

through a lateral port in the said collar, as indicated in dotted lines, Fig. 8, with a corresponding lateral port in the ring m^s , and with a pipe, n^s , which extends along the arm k^s , as shown in Fig. 1, out nearly to the wax-receptacle k^t , and is then turned back on itself and again enters the ring m^s , as indicated at n^s , Figs. 1 and 8, where it is connected through lateral ports, similar to those before described, with a stationary pipe, n^s , which passes from the stationary collar n^s , and is then led, as shown in Fig. 1, over to the upright a' of the machine, and then passes back and forth along the side of the raceway, as represented at n^s , Figs. 1 and 3, after which the end n^s of the pipe is carried to any desired point to discharge the steam and condensed water.

The collar n^s has a tubular hub (indicated in dotted lines at n^{20} , Fig. 8) extending along over the pin m^s and within the rings m^s and m^t , and the ring m^s is held in place on the tubular hub n^{20} by a nut, n^{21} , which may be turned up, so as to cause the ported side faces of the rings m^s , m^t , and n^s to bear against one another sufficiently to prevent leakage either of the steam or wax when passing from the stationary rings m^s , n^s into the ring m^t , that turns on the hub n^{20} with the arm k^s . The wax-reservoir and wax-receptacle and duct connecting them are thus retained heated, so that the wax flows readily to the receptacle and saturates the upper thread as it passes through the same, and the shuttle race and shuttle are also kept thoroughly heated by conduction from the pipe n^s , so as to keep the under thread in the proper state of pliability.

The take-up arm k^s is provided with an arm, k^s , connected by a link, k^{10} , with one arm of the lever k^{12} , the other arm of which is engaged and operated by a hub, k^{13} , on the main shaft b , and thus produces the vibrating movement of the take-up arm at the proper times, adjustability of this movement being provided for in the usual manner by a slotted connection between the link k^{10} and lever k^{12} , as clearly shown in Fig. 1. By having the waxing-receptacle fastened to and movable with the take-up the thread merely passes through the said receptacle in proportion as it is used, and is not drawn back and forth through the receptacle at every stitch, as is the case when the thread passes through a stationary waxing-receptacle located at some point between the stitch-forming devices and the take-up.

The tension-wheel k^s is provided with a brake, o , mounted on a lever, o' , pivoted on the arm k^s , and acted upon by a spring, o^2 , that normally forces it against the wheel k^s , so as to prevent the same from turning during the up-and-down movement of the take-up lever k^s . At the end of the upward movement of the said lever the end of the arm o' comes in contact with a cam, o^4 , on the frame a' , which raises it from the tension-wheel k^s , leaving the latter to turn with only resistance required to give the proper tension to the upper thread. The tension-wheel is thus released from the

brake just as the stitch is being formed and drawn up tight, and at this time the feed of the stock takes place and a sufficient amount of thread is drawn over the tension-wheel and 5 through the waxing-receptacle k^1 for the next stitch. At this time the looper or thread-guide e is back from the path of the needle and awl, as shown in Fig. 10, and the thread-measurer g is then turned from the position 10 with its forked end just under the eye of the thread-guide, as shown in Fig. 2, to the position shown in Fig. 10, and in this movement it engages the upper thread extending from the last stitch to the eye of the looper and 15 draws through the eye of the looper a portion of thread which it holds, as indicated in fine lines, Fig. 9. The needle then comes up and the looper swings around and carries the thread between its eye and the end of the 20 thread-measurer g into the hook of the needle, which then descends, and at the same time the arm k^2 descends, relaxing the thread extending from one side of the needle-hook, and the thread-measurer g turns back, relaxing the 25 thread at the other side of the needle hook, which thus draws down a loop of sufficient length to permit the shuttle to pass through without causing the thread to run in the hook of the needle, as would be the case if the 30 thread-measurer g were not used and the thread were carried by the looper direct from the last stitch into the hook of the needle. The point of the shuttle i is directly in line with the shaft of the needle, so that when the 35 shuttle is thrown forward it passes into and opens the loop held on the hook of the needle.

In order to prevent the loop from being dragged by the shuttle, a loop-pusher, t , may be employed, consisting of a finger, (best shown 40 in Figs. 1 and 2,) which rests against the side of the shuttle just in front of the loop, and holds or pushes the loop toward the rear end of the shuttle, so that the shuttle will not drag the loop along with it in passing through, and 45 when the shuttle has passed wholly through a loop of upper thread the loop-pusher or finger t is disconnected from the loop, which is also cast off or thrown out from the hook of the needle by the device u (see Figs. 4 and 5) 50 on the shuttle-carrier, consisting of a pair of yielding blocks supported on springs u' , Fig. 5, which pass over the hooked end of the needle, as shown in Fig. 4, pushing the thread out from the hook, and after this is done the 55 take-up arm k^2 makes its upward movement, drawing up the loop of upper thread, and with it the under thread, extending from the last stitch to the shuttle, as shown in Fig. 4. The under thread is at this time held with 60 sufficient tension to prevent it from drawing too far toward the upper surface of the material by a tension-pad, v , that clamps the thread between it and the shuttle, as shown in Fig. 4, and when this clamp is properly adjusted 65 the parts will operate to make a lock stitch on thick or thin stock without change of adjustment.

The actuating mechanism for the shuttle-carrier, loop-pusher t , and tension device v is as follows: The shuttle i is vibrated by the 70 shuttle-carrier r , that consists of a frame having a finger, r' , (see Fig. 5,) that engages a recess in the side of the shuttle, as shown in Figs. 3 and 5, and a projection, r^2 , that engages the rear end of the shuttle, which is 75 placed in the shuttle carrier by a lateral and downward movement, and then is confined therein by a fastening-plate, r^3 , Fig. 3, that fits in a dovetail guide, r^4 , and serves to hold the shuttle in the shuttle-carrier and shuttle-race. The shuttle-carrier is supported on an arm, r^5 , pivoted at r^6 at the front of the base a of the machine, and connected by a link, r^7 , with an arm, r^8 , on the rock-shaft d^1 , which is 80 provided with an arm, r^{10} , (see Fig. 1,) actuated 85 by a cam, r^{11} , on the main shaft b . The pivotal connections and the various arms are made adjustable to vary the throw of the operative parts in the usual manner.

The loop-pusher t is supported on a lever, 90 t' , pivoted at t^2 on a stud that is itself pivoted at t^3 on a bracket or frame piece, t^4 , fastened to the frame-work of the machine, as best shown in Fig. 3. The loop pusher t has an inward and outward movement toward and from the path of the needle, produced by the vibration of the lever t' on the stud t^2 , and is normally pressed inward, so as to bear against the side of the shuttle by a spring, t^5 , and thus catches the loop just as the point of the shuttle 95 enters it, as will be understood from Fig. 2. Then as the shuttle advances and the thicker or wider part comes opposite the loop pusher, the latter is moved outward by a lever, t^6 , (see Figs. 1 and 6,) having a cam-shaped end, t^7 , 100 (see Fig. 6,) that is engaged by the arm r^8 that actuates the shuttle. The rear end of the loop-pusher is turned laterally toward the rear of the shuttle, as clearly shown in Fig. 2, so that it tends to open the loop as well as hold it back 105 toward the rear end of the shuttle when it is moved out by the action of the lever t^6 as the shuttle advances. The movement of the lever t' around the pivot t^3 (see Fig. 3) tends to move the end of the loop-pusher in the line of movement of the shuttle, and it is normally held just in advance of the needle and loop by the 110 action of a spring-pressed plunger, t^8 , (see Fig. 6;) but just as the shuttle reaches its forward position a projection, t^9 , on the shuttle-carrier engages the arm t' , as best shown in Fig. 2, and moves the loop-pusher t in the same direction as the shuttle far enough to carry its laterally-projecting end out from the loop, so as to leave the latter free to draw up, 115 and at the same time the cast-off u also passes over the end of the needle, as shown in Fig. 4, pushing the loop out from the hook of the needle, so that it may now be drawn up by the 120 upward movement of the take-up arm k^2 .

The tension device or clamp v for the under thread that holds the thread between it and the shuttle, as best shown in Fig. 4, is supported on a lever, v' , (see Fig. 1,) provided 125

with an adjustable lever, v^2 , which, when the shuttle is in its forward position and the take-up lever k^2 is making its upward movement, is acted upon by a cam projection, v^3 , which forces it down on the under thread and holds the same, so that it will not be drawn up by the upper thread too near the upper surface of the material being sewed, and by properly regulating this device the lock of the upper and under threads will be formed just about midway between the upper and under surface of the material, as desired.

It will be noticed that the upper thread is not waxed until it has passed the tension-wheel k^3 , or just before it is presented to the stitch-forming devices, and consequently the tension-wheel and parts which operate to take up the loop are exposed only to dry thread, and consequently do not become gummed up, so as to interfere with their proper operation, as is the case when the thread is waxed before passing to these devices. Mounting the tension-wheel k^3 directly on the take-up lever and making it and its brake o a portion of the take-up mechanism greatly simplifies the machine, which can be operated with great rapidity and certainty, and the construction of the stitch-forming devices is such that they enter very little into the space around the work-support, so that the machine may be conveniently employed for stitching along the welt or edge of the sole of a boot or shoe without striking the upper.

The invention is not limited to the construction and arrangement of the parts shown for actuating the main stitch-forming devices, as this may be greatly varied, and will in practice be varied in accordance with the work that the machine is intended to perform, and no novelty is claimed for the construction and arrangement shown for these parts, the main features of novelty consisting in the devices for waxing the upper thread and heating the machine, in the take-up mechanism for the upper thread, the arrangement of the thread-measurer and its actuating mechanism with relation to the looper in the loop-pusher, and the clamp or tension device for the under thread.

50 I claim—

1. In a sewing-machine, a movable take-up and waxing-receptacle attached to and movable with said take-up, substantially as described.
2. In a sewing-machine, a movable take-up and waxing-receptacle fixed thereon, combined with pipes extending along the said take-up and maintained in communication with stationary pipes on the sewing-machine for the purpose of heating the said arm and waxing-receptacle, substantially as described.
3. In a sewing-machine, a movable take-up, combined with a waxing-receptacle fixed on said take-up, and a tension-wheel on said take-up, over which wheel the dry thread passes

into the waxing-receptacle, substantially as described.

4. The combination of the movable take-up and tension-wheel supported thereon with a spring-pressed brake connected with said take-up normally retained by its spring-pressure in engagement with said tension-wheel, and a stationary stop on the frame-work in position to be engaged by said brake in its movement produced by said take-up, substantially as and for the purpose described. 75

5. The needle and looper, combined with the thread-measuring device and its supporting sleeve or collar mounted on the shank of the looper, as set forth, and the actuating link, arms, and cam for the said thread-measuring device, which vibrates on an axis concentric with that of the looper, substantially as described. 80

6. The combination of a hooked needle, 85 shuttle and shuttle-carrier, and their actuating mechanism with a cast-off composed of yielding blocks that pass over the end of the needle and throw the thread out from the hook thereof, substantially as described. 90

7. The combination of the needle and shuttle with the tension device, consisting of a pivoted lever having a thread-holding portion that bears on the thread and clamps the same between said thread holding portion 95 and the body of the shuttle, and a rotating cam on the main shaft of the machine that operates the said tension device, substantially as described.

8. The combination of a needle and shuttle 100 with the loop engaging finger t and its supporting-lever and fulcrum-piece therefor, the said lever being pivoted on said fulcrum-piece, which is itself pivoted on the frame-work, combined with means for operating said 105 parts, substantially as described.

9. The combination of the vibrating take-up arm with a tension-wheel pivoted on said arm and accompanying the movements thereof, a spring-pressed lever, also pivoted on said arm 110 and provided with a friction-block that bears on the said tension-device and constitutes a brake therefor, and a stationary engaging device co-operating with said pivoted lever, as described, whereby the friction-block is disengaged from the tension device during the last part of the movement of the take-up in one direction, substantially as described. 115

10. In a sewing-machine, a vibrating take-up arm and waxing-receptacle thereon, combined with a wax-reservoir and passage connecting the same with said waxing-receptacle, substantially as described. 120

In testimony whereof I have signed my name to this specification in the presence of two subscribing witnesses. 125
